Primary Examiner—Mitchell Siegel

(74) Attorney, Agent, or Firm—Denton L. Anderson; Sheldon & Mak

(**) Term: **14 Years**

(57) **CLAIM**

(21) Appl. No.: **29/187,299**

The ornamental design of a soft ice cream dispenser, as illustrated in the specification.

(22) Filed: **Jul. 28, 2003**

DESCRIPTION

(30) **Foreign Application Priority Data**

Jan. 29, 2003 (CH) 129468

(51) LOC (7) Cl. **15-07**

FIG. 1 is a perspective view of the soft ice cream dispenser of the invention;

(52) U.S. Cl. **D15/82**

FIG. 2 is a front view of the soft ice cream dispenser illustrated in FIG. 1;

(58) Field of Search D15/79, 80, 82; D7/376; 62/340, 342, 343, 344, 371

FIG. 3 is a first side view of the soft ice cream dispenser illustrated in FIG. 1;

(56) **References Cited**

FIG. 4 is a second side view of the soft ice cream dispenser illustrated in FIG. 1;
